(76) Inventor: **Samuel Randall**

Samuel Randall
Letter Patent

The schedule referred to in the Letter Patent and making part of the same containing a description in the words of the said Samuel Randall himself of his mode of tracing to write,

The skeleton (or form) of Letters, signs &c are formed on paper by colouring all parts of it except the skeleton (or form) of the Letters (or signs) all parts of the paper are to be coloured except when the pen is to be drawn to form the Letters or figures at least so much of it coloured as will make the skeleton (or form) at once discernable to the practitioner or pupil.

This is done by engraving whatever is desired should be written on the surface of any kind of metal. The colouring is then spread over said surface. The paper is then laid and pressed upon it which will colour all parts of the paper except those parts the engraving them will be no thicker than skeleton. The pupil is to trace with a pen. These skeletons may be formed any other way which experience shall prove most expedient. The above I hereby acknowledge to be the description of the improvement under consideration.
